[57] CLAIM

The ornamental design for an article display stand, substantially as shown and described.

DESCRIPTION

FIG. 1 is a reduced perspective view of the article display stand showing my new design;

FIG. 2 is a side elevational view of FIG. 1;

FIG. 3 is a top plan view of FIG. 1;

FIG. 4 is a sectional view taken on line 4—4 of FIG. 2;

FIG. 5 is a perspective view of a second embodiment of the design of FIG. 1;

FIG. 6 is a front elevational view of FIG. 5;

FIG. 7 is a top plan view of FIG. 5.

FIG. 1.

FIG. 2.

FIG. 3.

FIG. 4.

FIG. 5.

FIG. 6.

FIG. 7.
